CABLE STRIPPING DEVICE

Frank Benjamin Stark, Wermleysburg, Pa., assignor to
AMP Incorporated, Harrisburg, Pa.
Filed June 29, 1965, Ser. No. 467,875
6 Claims. (Cl. 30—90.1)

This invention relates to a hand operated rotary cutter and cutting method, and more particularly to a simplified cutting device for dressing or marking the ends of coaxial and shielded wire cables.

Various cutting devices have been evolved for stripping insulated shielded wire and cable and for cutting non-metallic tubing. Some of these prior devices include intricate cable positioning, holding and cutting means with activating arms and levers, and some include multi-piece housings. These devices are usually cumbersome, difficult to operate and expensive to make. The present cutting device is a one piece tubular member with a longitudinal bore partly therethrough and with spaced step-wise slots thereacross. The end of a cable to be dressed is entered into the device via the longitudinal bore, and a cutter blade is utilized in the transverse slots, one slot at a time while the device is rotated about the cable. This strips the cable and prepares it for termination. The cutter device may be held stationary and the cable rotated within the device if desired.

It is therefore an object of the present invention to provide a new and improved device for dressing the ends of coaxial cables and insulated conductors.

Another object is to provide a device of this nature which is compact, portable, easy to use and inexpensive to manufacture.

Another object is the provision of a rotary cutter device which will dress the ends of cables without injuring or fraying the underlayers or the shielding.

Still another object is the provision of a cutter device which enables the measurement and/or marking of the length of the conductor lead and cable braid to be exposed in the stripping process.

Other objects and attainments of the present invention will become apparent to those skilled in the art upon a reading of the following detailed description when taken in conjunction with the accompanying drawings in which there is shown and described an illustrative embodiment of the invention; it is to be understood, however, that this embodiment is not intended to be exhaustive nor limiting of the invention, but is given for the purpose of illustration in order that others skilled in the art may fully understand this invention and the principles thereof and the manner of applying it in practical use so that they may modify it in various forms, each as may be best suited to the conditions of a particular use.

In the drawings:

FIGURE 1 is an exploded perspective view showing a cable being inserted into a cutter device in accordance with the present invention;

FIGURE 2 is a perspective view showing the cutter device in operation;

FIGURE 3 is a cross-sectional view taken through the cutter device of FIGURE 1;

FIGURE 3a is a side elevational view of the cutter device of FIGURES 1 and 2; and

FIGURES 4 to 6 are views of successive stages in the cable dressing operation.

Referring now to the drawings and particularly to FIGURE 4, the rotary cutter device C of the present invention embodies a tubular member 2 having a central bore 3 with one end thereof partially closed by a wall 4.

Bore 3 is formed of a suitable diameter to accept the smallest to the largest cable in a given cable range,

2

e.g. RG59, RG62, RG140 and RG210. The above cables are generally the same size in cable O.D., braid O.D., dielectric O.D. and conductor diameter, but vary slightly in construction and materials. Wall 4 constitutes a positioning means to accommodate a cable end bottomed upon insertion of the cable W into the cutter device. A sight hole 6 is provided in wall 4 to allow the operator to inspect the end of cable W for its proper positioning within cutter C.

5 First, second and third slots, 8, 9 and 10 respectively, are formed in step-wise array in the bore 3 of member 2. Each slot has substantially the same width, but each is of successively greater depth beginning from first slot 8. Slots 8, 9, and 10 are identified by marking numbers; e.g., 1, 2, and 3, which are embossed or engraved on the outer surface of the device (FIGURE 3a). This arrangement permits cuts to be made onto cable or wire in a desired sequence. Bore 3 of member 2 is of sufficient diameter to enable any one of a number of coaxial cables W within a given cable range to be inserted therein. The depths to which slots 8, 9 and 10 are cut are respectively equal to the thickness of insulation layer 12, the combined thickness of insulation layer 12 and braid layer 14, and the total thickness of insulation layer 12, 20 braid layer 14 and cable dielectric layer 16 of cable W, FIGURES 4, 5 and 6.

25 A cutter blade B, e.g. razor blade or knife blade, is utilized in slots 8, 9 and 10 the combination of which constitutes the cutting means by which predetermined lengths of cable layers are stripped from cable W thereby dressing the end of the cable for subsequent termination to a component.

30 In operation, the end of a cable W is inserted into the cutter device C, FIGURE 1, and bottomed against wall 4. The center conductor CD of cable W will be clearly visible at sight hole 6. A cutter blade B is inserted into slot 10 and biased against cable W by one finger of the operator, FIGURE 2. The cable W may be rotated within cutter device C, or the device

35 may be rotated about cable W, whichever is desirable. This rotation causes cutter blade B to sever layers 12, 14 and 16, but does not allow blade B to touch or otherwise nick center conductor CD, FIGURE 4. After a number of rotations, blade B is withdrawn from slot 10 and entered into slot 9. The same above rotation procedure is administered at this slot. During this rotation, a cut is made equal to the thickness of layers 12 and 14 which ultimately exposes a short length of cable dielectric, FIGURE 5. The same rotation procedure is then administered with blade B in slot 8. This cut is through insulation layer 12 but not through braid layer 14. The cable is withdrawn from the device with the various layers and combinations being then pulled from the end of the cable. The result is a properly stripped and dressed cable end having a suitable length of exposed center conductor CD, a short section of cable dielectric 16 behind conductor CD and a length of cable braid 14 continuous over dielectric 16, FIGURE 6.

40 It should be noted that the closed end section of the cutter device C may be knurled as indicated at K or otherwise serrated, FIGURE 1, to facilitate the operation of the device. Slots 8, 9 and 10 respectively may be numbered 3, 2 and 1, respectively, or otherwise coded to assure proper sequential operation of the device. The device may be numbered or color coded to assure its proper use relative to a given cable range.

45 The cutter device of the present invention may be used as a marking device to mark a cable for subsequent cutting. This is desirable on special cables having extremely hard jackets and dielectric layers. In this case, the cable is marked by using the cutter blades

in the slots of the device whereafter the cable is removed from the device and cut by hand. The cutter device of the present invention is not limited to three slots, but may have any suitable number of slots to accommodate cables of various construction.

It should also be noted that a rotary cutter device in accordance with the present invention may be used to cut pre-determined lengths of plastic or other non-metallic tubing.

It will, therefore, be appreciated that the aforementioned and other desirable objectives have been achieved; however, it should be emphasized that the particular embodiment of the invention which is shown and described herein, is intended as merely illustrative and not as restrictive of the invention.

What is claimed is:

1. A rotary cutter device for dressing the ends of coaxial cable comprising in combination a tubular member and a cutter blade, said tubular member having a series of transverse axially spaced slots of different depths related to the radial thickness of the layers of the cable for imposing spaced cuts of different depths in said cable, said tubular member slots being of a width to receive and limit the insertion of said cutter blade to assure proper cuts in said cable and, said tubular member further having means at one end defining a stop for cable entered therein which is axially spaced from said slots to accurately position the cable within said tubular member relative to said slots and pre-determined lengths of cable conductor, cable dielectric and cable braid to be exposed or removed.

2. The device of claim 1 wherein said slot depths increase in proportion to the axial spacing thereof from said stop means.

3. A tool for stripping the ends of coaxial electrical cable comprising in combination a tubular member and a cutter blade, gauge means in said tubular member for imposing spaced cuts of varying depths in said cable, said tubular member including an axial bore adapted to receive and support a cable inserted therein, said gauge means being comprised of a number of spaced transverse slots through a side wall of said tubular member,

which are of a width to receive and limit the insertion of said cutter blade therein for imposing said spaced cuts of varying depth in said cable, said bore being closed on one end thereof by an end wall defining a stop means for cable inserted therein with said wall including an aperture for visual inspection to assure proper cable position within said tubular member.

4. The tool of claim 3 wherein said slots are angularly disposed with adjacent slots in different segments of walls of said tubular member.

5. The tool according to claim 3 wherein said aperture is comprised of a small longitudinal opening in said end wall concentric with the center conductor of said cable whereby said center conductor is visible to the operator of said cutter device when said cable is in proper position in said cutter device, during the stripping operation.

6. A tool for stripping insulated coaxial and shielded cable comprising a cylindrical member having a central bore partly therethrough to receive a cable end, wall means on one end of said bore, inspection means in said wall means including a hole for inspecting said cable end inside said bore, and slot means on said cylindrical member to receive a cutting blade for performing a series of spaced cuts of different depths in said cable to remove layers thereof of a desired axial length whereby to strip cable, said slot means being marked to permit all of said cuts to be accomplished in a desired sequence or to permit any one of said cuts to be made separately.
